UNITED STATES PATENT OFFICE

133,202

DESIGN FOR A LAPEL BUTTON OR SIMILAR ARTICLE

John F. Alexander, Potlatch, Idaho

Application February 23, 1942, Serial No. 105,957

Term of patent 7 years

To all whom it may concern:

Be it known that I, John F. Alexander, a citizen of the United States of America, residing at Potlatch, in the county of Latah and State of Idaho, have invented a new, original, and ornamental Design for a Lapel Button or Similar Article, of which the following is a specification, reference being had to the accompanying drawing, forming part thereof.

Figure 1 is a front elevational view of a lapel button or similar article showing my new design; and

I claim:

The ornamental design for a lapel button or similar article, substantially as shown.

JOHN F. ALEXANDER.
